UNITED STATES PATENT OFFICE.

CARL G. HEIBY, JOHN BURKAM, DAVID E. LINDQUIST, FRED L. RIGGIN, EBENEZER W. ALLEN, AND RICHARD LAU, OF SARNIA, CANADA, ASSIGNEES, BY MESNE ASSIGNMENTS, TO MUELLER METALS COMPANY, OF PORT HURON, MICHIGAN, A CORPORATION OF MICHIGAN.

BASE-PLUG FOR TIME-FUSES.

1,331,921.

Specification of Letters Patent.

Patented Feb. 24, 1920.

Application filed January 17, 1918. Serial No. 212,231.

To all whom it may concern:

Be it known that we, CARL G. HEIBY, JOHN BURKAM, DAVID E. LINDQUIST, FRED L. RIGGIN, EBENEZER W. ALLEN, and RICHARD LAU, all citizens of the United States except ALLEN, a subject of Great Britain, residing at Sarnia, in the county of Lambton and Dominion of Canada, have invented new and useful Improvements in Base-plugs for Time-Fuses, of which the following is a specification.

The present invention relates to forgings and particularly to forgings for base plugs for time fuses.

It has for its object to produce a forging by the use of which the work of machining and boring to produce the finished base plug is very materially reduced, and there is a resultant saving in time and labor.

In order that the invention may be clear to those skilled in the art there is shown in the accompanying drawings the several steps incident to the production of the specific article herein shown to illustrate the invention, namely, a base plug for time fuses, the forging steps in the method from the slug to the finished product being shown.

In said drawings:

Figure 1 is a view of a blank or slug suitable for the production of these articles.

Fig. 2 is a view in section of the slug after it has been subjected to the action of the forging dies and before trimming.

Fig. 3 is a view in section of a trimmed forging.

Fig. 4 is a view in section showing a finished base plug.

Referring to the drawings by numerals, like numerals indicating like parts in the several views, 10 indicates the plug which may be formed in any convenient manner either by casting as an individual slug, or it may be produced by cutting from a cast, or rolled or drawn rod, lengths of the requisite size to form a slug appropriate for the article to be produced, these slugs being formed with a cubical content but slightly in excess of the cubical content of the article to be made. In the particular form of slug here shown, there is illustrated a cast slug, and in casting these individual slugs, there is at the top of the casting a slight amount of impure metal and dross, which impure

surface will be machined off to the dotted line 11 before the slug is subjected to the forging operation so as to leave a body of pure metal.

The slug freed of its incrustation of dross will then have formed in one end or the other a slight depression 12 which serves initially as a means to engage a complementary part on one of the die members so as to center the slug accurately between the dies. The slug will then be subjected to the action of the dies and brought to the form shown in Fig. 2 having the body portion 13, the upstanding annular wall 14 with the central cavity 15, the lower part of the forging having the projection 16 as shown. The forging in this form as it comes from the dies has the annular projecting fin or flash 17 made up of that slight excess of metal over and above what is needed for the body of the forging.

In Fig. 3 the forging is shown just prior to machining and finishing, and after the flash 17 has been trimmed from the body portion 13, and in this form the forging is exteriorly in practically completed condition in that it is necessary only to remove so much of the metal as will bring the exterior surfaces to finished form, or to that threaded condition which certain portions of the exterior have when the base plug is finally completed. Interiorly, the forging shown in Fig. 3 is completed in the sense that the cavity 15 and the depression 12 are so placed and formed as to give an interior form which lessens very substantially the machining and boring which have to be done.

In Fig. 4, the finished base plug is shown, and it will be observed that except for the interior borings, which are slight, there is but little change over the completed forging shown in Fig. 3. As stated, the outside of the forging will, of course, be machined to a proper finish, but this calls for only the removal of a slight amount of metal, in fact, practically nothing but the slightly roughened skin of the forging as it comes from the press. The body portion 13 is screw-threaded as shown, it being necessary to remove only so much of the metal as is necessary to give the proper threading; the cavity 15 is given a proper finish, and the depression 12 is similarly machined out

and brought to the circular form shown at 18 in Fig. 4. Such other boring and slotting as is necessary is of relatively slight character so that it is obvious that the main 5 part of the work is done by the die press, and but little of the laborious and slow machine work is necessary.

We claim:—

1. A forging for fuse base plugs having a body portion, an annular rim of less diameter than said body portion projecting therefrom and having forged therein a central cavity, and a projection from the other end of said body portion having formed 15 therein a cavity or depression.
2. A forging for fuse base plugs having a body portion, a projection from said body portion having a cavity forged therein of substantially the area of the cavity of the 20 finished plug and forming an upstanding annular wall rising from said body, and a projection from the other end of said body

portion having formed therein a cavity or depression.

3. A forging for fuse base plugs comprising a disk-like body portion of substantially the same size as the body of the finished plug, a projection from said body portion having a cavity forged therein of substantially the area of the cavity of the 30 finished plug and forming an upstanding annular wall rising from said body, and a second projection forged on the opposite end of said body portion and having formed centrally thereof a cavity or depression. 35

In testimony whereof we have hereunto set our hands.

CARL G. HEIBY.
JOHN BURKAM.
DAVID E. LINDQUIST.
FRED L. RIGGIN.
EBENEZER W. ALLEN.
RICHARD LAU.
